ELECTRICAL CONTROL CIRCUIT

Herbert Belar, Philadelphia, Pa., assignor to
 Radio Corporation of America, a corporation of
 Delaware

Application December 24, 1937, Serial No. 181,588

6 Claims. (Cl. 179—1)

This invention relates to electrical circuits such as are utilized to control the amplification of different signal channels, the fading of one signal channel to another and the mixing of the outputs of associated signal channels. It has for its principal object the provision of an improved system and method of operation whereby these various results may be achieved without the difficulties heretofore incident to their realization.

As applied to the gain control of different signal channels, the improved system affords a ready means of controlling the gain of a plurality of channels either together or individually without undesirable interaction between the different channels. It also makes feasible such gain control from a plurality of different points such as a projection booth and a theater auditorium or the like.

As applied to fading from one signal channel to another, the improved system affords a simple means of changing from one channel to another whether the channels be utilized in connection with sound motion picture recording, sound motion picture reproducing, a radio broadcast station or the like.

As applied to the mixing of the outputs of different signal channels, the improved system is especially applicable to sound recording, radio broadcasting and the like.

An additional feature of the improved system is the provision of means for preventing interaction between two channels which feed into a single output or mixer stage.

The invention will be better understood from the following description considered in connection with the accompanying drawings and its scope is indicated by the accompanying claims.

Referring to the drawings:

Figure 1 illustrates a modification of the invention wherein a plurality of signal channels are arranged to have their gains controlled either independently or simultaneously and are provided with means for readily fading from one of the channels to the other.

The arrangement of Fig. 2 is similar to that of Figure 1 except that provision is made for controlling the gain of the signal channels from different locations.

Figure 3 illustrates a modified form of the arrangement of Fig. 2.

Figure 4 illustrates a plurality of signal channels which are arranged to fade into a single output or mixer stage, are provided with means for preventing interaction between the different signal channels, and with gain control and

fading means similar to those of the previous figures, and

Figure 5 is a wiring diagram illustrating certain details of the circuit of Fig. 4.

The system of Fig. 1 includes a plurality of signal channels represented by the electron discharge devices 10 and 11. These channels are respectively provided with the usual signal input circuits 12 and 13. Bias potential for controlling the gain of the two signal channels is derived from a potential source 14 and a potential source 15 which is shunted by a resistor 16 provided with an adjustable terminal 17. Connected at the positive terminal of the battery 14 and the adjustable terminal 17 are a resistor 18 provided with an adjustable terminal 19 and a resistor 20 provided with an adjustable terminal 21, a switch 22 being provided in the high potential connection of the resistor 18 and a switch 23 being provided in the high potential terminal 20 of the resistor 20. Interposed between the input circuit 12 and the adjustable terminal 19 and resistor 18 is a resistor 24. Similarly interposed between the adjustable terminal 21 and the resistor 20 and the input circuit 13 is a resistor 25. It will be readily understood that the output circuits 26 and 27 of the devices 10 and 11 may be connected through additional stages to a utilization device such as the loudspeaker of a sound motion picture reproducing equipment.

In the operation of the channels 10 and 11 the gain of the channel 10 is individually controlled by adjustment of the terminal 19 of the resistor 18, the gain of the channel 11 is individually controlled by adjustment of the terminal 21 of the resistor 20 and the gains of the two channels are simultaneously controlled by adjustment of the terminal 17 of the resistor 16. Assuming the switches 22 and 23 to be closed and both channels to be in operation, the signal is faded from the channel 10 to the channel 11 by opening of the switch 22 which functions to increase the negative bias potential applied to the control grid of the device 10, thus closing this device to the signal. Similarly, the signal is faded from the device 11 to the device 10 by opening the switch 23 which increases the negative bias applied to the input circuit of this device.

Fig. 2 illustrates a system which is similar to that of Fig. 1 but differs therefrom in that provision is made for controlling the gains of the two channels from different locations, such, for example, as the projection booth and auditorium of a sound motion picture theater. In this fig-

ure corresponding parts are indicated by the same reference numerals, as in Fig. 1. Potential for controlling the bias of the input circuits 12 and 13 is derived from the battery 14 through resistors 28 and 29 in the case of the device 10 and through resistors 30 and 31 in the case of device 11. The gain of the device 10 may be controlled from one point by the resistor 28 and from another point by the resistor 29. Similarly, the gain of the device 11 may be controlled from one point by the resistor 31 and from another point by the resistor 30. As will be readily understood, the resistors 28 and 31 may be located in a motion picture projector booth and the resistors 30 and 31 may be located in the auditorium. It will be noted that the range of control possible at the resistors 28 and 30 is dependent on the position of the adjustable terminal of the resistor 28. This, of course, results in a somewhat limited control at one of the control points.

By connecting the resistors 28 and 29 in a closed loop or circle such as the resistor 32 of Fig. 3 equal freedom of control points may be realized. This arrangement, of course, involves the connection of a considerable number of leads between the two points. In the projection booth, for example, a contact member 33 connected to the lower terminal of the resistor 24 is rotated to engage the various contacts of the resistor 32 and applied to the input circuit 12. A bias potential which is variable from that point located in the auditorium may be a rotatable insulation arm 34 provided at its opposite ends with brushes 35 and 36 arranged to engage a plurality of contacts similar to those of the resistor 32 and to apply to the engaged contact the potential of the source 14. It thus follows that the arm 34 may be moved to advance the axis at which the potential of the source 14 is applied to the resistor 32 and that the member 33 may be moved to select any desired part of this potential. This, of course, makes possible at either location freedom in the control of the gain of the device 10. It should be noted that the arrangement of Fig. 3 may be duplicated in the same manner as the arrangement of Fig. 2 for the purpose of controlling the gain of more than one channel and may also be provided at suitable points with the fading switches 22 and 23 of Figs. 1 and 2.

The system of Fig. 4 illustrates the channels or devices 10 and 11 as arranged to feed into a single output channel or stage 37. It will be noted that the device 10 is coupled to the input circuit of the device 37 through a capacitor 38 and that the device 11 is similarly coupled to this input circuit through a capacitor 39. In order to perfect interaction between the operation of the device 10 and that of the device 11, resistors 40 and 41 are connected in series between the capacitors 38 and 39 and are provided with an intermediate terminal from which the mixed signal is applied to the input circuit of the device 37. As in the previous modifications of the invention the gain of the device 10 is controlled through the resistor 19, the gain of the device 11 is controlled through the resistor 20 and the gains of the devices 10 and 11 are simultaneously controlled through the resistor 16. Otherwise the gain of the output device 37 is individually controlled through a resistor 42 and is simultaneously controlled together with the gains of the devices 10 and 11 through the resistor 16.

For fading from the device 10 to the device 11 a three position switch 43 is provided. In the

illustrated position of this switch both the device 10 and the device 11 are arranged to supply to the input of the device 37 a mixed output which is dependent on the adjustment of the resistors 18 and 20. Movement of the switch 43 into engagement with the contact 44 increases the negative bias applied to the input of the circuit 11 and transfers the signal to the device 10. Likewise movement of the switch 43 into engagement with the contact 45 transfers the signal from the device 10 to the device 11.

The arrangement for preventing the operation of one of the devices from affecting the operation of the other is indicated somewhat more clearly in Fig. 5. It will be understood that the function of the resistors 40 and 41 is to present to the output circuit of the two devices an impedance which effectively isolates the one from the other. It is evident that the arrangement of Fig. 4 may be provided with either the circuit of Fig. 2 or the circuit of Fig. 3 where it is desired to control the different channels from different locations, the showing of this feature in connection with Fig. 4 being omitted to simplify an understanding of the invention.

I claim as my invention:

1. The combination of a plurality of signal channels, a single signal channel provided with an input circuit, impedance means interposed between the outputs of said plurality of channels for preventing interaction therebetween and for applying to said input circuit a control potential dependent on the combined outputs of said plurality of channels, means for independently adjusting the gain of said plurality of channels and of said single channel, and means for simultaneously adjusting the gain of all of said channels.

2. The combination of a plurality of signal channels, a single signal channel provided with an input circuit, impedance means interposed between the outputs of said plurality of channels for preventing interaction therebetween and for applying to said input circuit a control potential dependent on the combined outputs of said plurality of channels, means for independently adjusting the gain of said plurality of channels and of said single channel, means for simultaneously adjusting the gain of all of said channels, and means for fading from one to another of said plurality of signal channels.

3. The combination of a plurality of signal channels, means including a bias potential source and a plurality of resistors connected in parallel to said source for independently adjusting the gains of said channels, and means including a resistor connected to a part of said source and provided with a contact connected to the low potential terminal of each of said parallel resistors for simultaneously adjusting the gain of said channels.

4. The combination of a plurality of signal channels, means including a bias potential source and a plurality of resistors connected in parallel to said source for independently adjusting the gains of said channels, means including a resistor connected to a part of said source and provided with a contact connected to the low potential terminal of each of said parallel resistors for simultaneously adjusting the gain of said channels, and means for interrupting the high potential terminal of each of said parallel resistors for fading from one of said channels to another.

5. The combination of a plurality of signal channels, means including a bias potential source and a plurality of resistors connected in parallel

to said source for independently adjusting the gains of said channels, means including a resistor connected to a part of said source and provided with a contact connected to the low potential terminal of each of said parallel resistors for simultaneously adjusting the gain of said channels, and means for controlling the gain of said amplifiers from a plurality of different points.

5. The combination of a plurality of signal

channels having respective input circuits, means for independently controlling the transmission in each input circuit, means for simultaneously controlling the transmission in all of said input circuits, and means individual to each of said signal channels for fading from one to another of said signal channels.

6. The combination of a plurality of signal

HERBERT BELAR.
